(57) **CLAIM**

The ornamental design for a ceiling fan blade bracket as shown and described.

DESCRIPTION

FIG. 1 is a front top perspective view of a ceiling fan blade bracket showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front bottom perspective view thereof.

The broken lines illustrate portions of the ceiling fan blade bracket that form no part of the claimed design. Unshaded surfaces adjacent to broken lines form no part of the claimed design.
